UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

DRAFT-GEAR.

1,184,022.

Specification of Letters Patent. Patented May 23, 1916.

Application filed April 11, 1913. Serial No. 760,477.

To all whom it may concern:

Be it known that I, JOHN M. ROHLFING, residing at St. Louis, Missouri, and being a citizen of the United States, have invented 5 certain new and useful Improvements in Draft-Gear, of which the following is a full, clear, and exact description, such as will enable others skilled in the art to which it appertains to make and to use the same, reference being had to the accompanying drawings, which illustrate the preferred form 10 of the invention, though it is to be understood that the invention is not limited to the exact details of construction shown and 15 described, as it is obvious that various modifications thereof will occur to persons skilled in the art.

In said drawings: Figure 1 of the drawings is a horizontal section taken through 20 the supporting beams and showing the gear in full assembled position. Fig. 2 is a elevational view of the device, parts of which are broken away to more clearly show the drawbar and yoke connection. Fig. 3 is a 25 plan of the parts arranged for both swiveling and longitudinal movement of the coupler within the yoke. Fig. 4 is an elevational view with parts broken away to show connection of yoke to drawbar. Fig. 5 is a 30 a fragmentary plan view of the lower portion of the slotted upset yoke arm, the inner faces of which have sliding engagement with the drawbar. Fig. 6 is an inverted plan of the connecting block used in the arrangement shown in Figs. 3 and 4. Fig. 7 is a 35 similar view of the connecting block as used in the device shown in Figs. 1 and 2.

The principal object of the invention is to provide a gear of such form as to be 40 capable of use in cars having limited space between the car bolster and car end.

Another object is to provide a gear in which a drawbar of standard design is permitted a relatively longitudinal movement 45 within a yoke of approved form and dimension.

A further object is to provide a gear in which the connection between drawbar and yoke is sufficiently elastic to permit relative movement thereof caused by the surging 50 of the cars in the train.

With the above objects in view the invention consists generally in the combination of the drawbar, the slotted yoke arms, 55 connection blocks or thimbles, having slid-

ing engagement with the yoke, and a cushioning means.

The device is designed for use with the Cardwell spring arrangement but may be assembled with a cushioning element of any 60 type. The helical spring and followers shown in the drawings are introduced only for the purpose of illustrating a cushioning element in the assembled structure.

In the drawings, H represents the draft 65 beams forming part of the underframe of a car and between which the gear is arranged. For the convenience of illustration that portion only of the draft beams is shown which extends from a short distance 70 beyond the bolster to the end of the car. O is the bolster filler casting arranged between the draft beams and adapted to prevent excessive rearward movement of the yoke; C is the striking casting provided 75 with rearward extensions K which operate as front stops for the follower B, and, as shown in Fig. 1, the inner sides of the extensions K diverge outwardly to permit the draw bar and yoke, or the draw bar alone, 80 to have transverse swinging movement, such as one or both of these parts, according to the type of draft gear in use, will acquire when the car carrying the draft gear encounters a curve; E represents the rear follower 85 which normally and during the buffing operation bears against abutments R on the bolster filler; G is the yoke having slotted forward extensions 1 embracing a drawbar 2. The inner or butt end of the 90 shank of said draw bar has upwardly and downwardly directed extensions which have top and bottom horizontal plane surfaces adapted to have sliding engagement with the inner surfaces of the horizontal legs of the 95 yoke G.

Since there is no relative movement of rear follower E and yoke G, these parts may be formed integral with each other.

The butt end of the draw bar is arranged 100 within the yoke G and between slotted extensions 1 and connected therewith by means of thimbles 3 and rivets 4 secured to drawbar, said thimbles being tightly held against the hereinbefore referred to top and bottom horizontal plane surfaces of the extensions on said butt end of the draw bar. The thimbles 3 are relation-preserving means apertured for the passage of said rivets 4, and are each provided with a retaining 110

flange 5 which laps the metal surrounding the slot 6, and said thimbles move with the drawbar to maintain the yoke arms in proper spaced relation.

5 It will be observed that the throats or shanks 7 of the thimbles are deeper than the thickness of the yoke metal surrounding the slots 6. This is for the purpose of allowing a slight spreading movement of the yoke arms produced by the action of the moving drawbar between them.

10 The elliptical shaped throats 7 of the thimbles 3, shown in Figs. 1, 2 and 7 are made long enough to receive two drawbar rivets 4 and are narrowed to present plane faces adapted to bear against the side walls of the slots 6. The shape of the thimbles is such as to permit very little, if any, radial movement of the drawbar or coupler within 15 the yoke.

15 In Figs. 3, 4, 5 and 6 the thimble 3^a is arranged to permit both a swiveling and sliding movement of the drawbar within the yoke. With the device so arranged, the 20 slots 6^a in the yoke arms are widened to accommodate the increased width of said thimble. In this arrangement also, the pressure exerted by the spring 10 against the 25 front follower and through said front follower against the rear plane face 11 of the butt end of the coupler will cause the drawbar to automatically return to its normal 30 position within the yoke, that is in line with the central longitudinal axis of the car.

35 To compensate for the material of the yoke omitted to form the slots or openings 6—6^a, I prefer to form the end portions 1 thicker than the loop portion, which is adapted to receive the draft gear elements, 40 and it is to be noted that the end portions 13 of the yoke are of sufficient section to lap the front edge of the coupler or drawbar, as shown in Fig. 2, so that draft stresses are 45 transmitted from the drawbar to the yoke without straining the aforementioned thimbles 3 or rivets 4.

50 As previously stated, the bolster filler casting O prevents excessive rearward movement of the yoke, which is highly desirable in view of the propinquity of the rear end of said yoke and the cylindrical portion of the casting which forms a bearing for the king pin. Said bolster filler casting O, as clearly shown in Figs. 1 and 2, is provided 55 with horizontal webs 14 and a centrally located vertical web 15, and when the draft gear is subjected to a buffing stress, the yoke G is prevented from moving too far rearwardly by these webs, thus avoiding the 60 danger of said yoke striking said cylindrical bearing, and the stress is absorbed by the spring 10.

Concerning the front follower B, it will be seen by consulting Figs. 3 and 4 that said 65 follower bears against the inner end of the

draw bar and is pressed thereagainst by spring 10. As a result, the draw bar is rocked by said follower and spring to return to a normal central position after the removal of any influence which caused it to 70 swing laterally.

What I claim is—

1. In combination, a draw bar and a yoke provided with openings therethrough of different areas, the lateral dimensions of the 75 yoke openings exceeding those of the draw bar openings, upwardly and downwardly directed integral extensions on the inner end of said draw bar, said extensions having horizontal plane surfaces slidably engaging 80 said yoke, apertured relation-preserving means slidably mounted in said yoke openings and bearing against said horizontal plane surfaces, and securing means projected through the openings in said draw bar 85 and relation-preserving means to connect the yoke and draw bar in sliding relation.

2. In combination, a draw bar having perforations, a yoke provided with openings in alinement with but larger and wider than 90 said perforations, upwardly and downwardly projecting integral extensions on the inner end of said draw bar, said extensions having horizontal plane surfaces slidably engaging said yoke and forward upstanding 95 plane surfaces, draft stress-receiving portions on said yoke adapted to be engaged by said forward plane surfaces, members slidably and rotatably mounted in said yoke openings, and bearing against said horizontal plane surfaces to connect said yoke and draw bar in pivotal and slidable engagement, and means projecting through said draw bar perforations and said members to 100 secure them together.

3. A draw bar, upwardly and downwardly projecting integral extensions thereon, a yoke having stress-receiving portions lapping and adapted to be intermittently engaged by said extensions, openings in said 110 yoke, slidably pivoting thimbles having flanges lapping said yoke and movable with said draw bar in said openings directly secured to said draw bar and adapted to connect said draw bar and yoke in slidable and 115 rotating relation, in combination with resilient means adapted to rock said draw bar at predetermined times, said means comprising front and rear followers positioned within said yoke, the front follower bearing against said draw bar, and resilient pressure-producing means interposed between said followers.

4. In combination, a draw bar, outwardly shouldered integral extensions thereon, a 125 yoke, stress-receiving portions on the latter adapted to be intermittently engaged by said shoulders, said yoke having relatively large openings therein, slidably thimbles of less sectional area than said openings seated 130

therein and movable with said draw bar independently of the yoke and directly bearing against said extensions, and means for securing said thimbles to said draw bar to 5 cause both to have a slidable connection with said yoke.

5. In combination, a draw bar, upwardly and downwardly projecting integral extensions thereon, a yoke, stress-receiving portions 10 on the latter, said yoke having relatively large openings in reinforced portions thereof, slidable thimbles movable with said draw bar independently of said yoke mounted in said openings, said slidable thimbles 15 lapping said yoke and means connecting said thimbles to said draw bar and locking them against relative rotary movement.

6. In combination, a yoke provided with relatively large openings in its end portions,

integral stress-receiving portions on said 20 end portions, a draw bar slidably held within said yoke, transversely disposed integral extensions on said draw bar adapted to engage said stress-receiving portions, removable thimbles connected positively to said 25 draw bar lapping said yoke and slidably mounted in said openings and bearing against said extensions, and connecting elements attaching said removable thimbles to said draw bar causing them to act as an integer. 30

In witness whereof I have hereunto set my hand in the presence of two witnesses.

JOHN M. ROHLFING.
